UNITED STATES PATENT OFFICE.

CLARENCE C. CRALEY, OF MOUNT JOY, PENNSYLVANIA.

METAL-WORKING MACHINE.

1,285,628.

Specification of Letters Patent. Patented Nov. 26, 1918.

Application filed November 17, 1917. Serial No. 202,596.

To all whom it may concern:

Be it known that I, CLARENCE C. CRALEY, a citizen of the United States, residing at Mount Joy, in the county of Lancaster and 5 State of Pennsylvania, have invented certain new and useful Improvements in Metal-Working Machines, of which the following is a specification.

The present invention relates to metal 10 working apparatus of the type disclosed in my Patents Nos. 1,007,185, dated October 31, 1911, and 1,217,572, dated February 27, 1917.

The primary object of the present invention is to provide a guiding means for the 15 slide bearings to insure a reasonably tight fit and prevent dirt or dust entering said bearings and thereby affecting the accuracy of the apparatus.

An embodiment of the invention is illustrated in the accompanying drawings, 20 wherein:—

Figure 1 is a perspective view of the bed of the machine, with the parts broken away to illustrate the bearing elements,

25 Fig. 2 is an end elevation of the same,

Fig. 3 is a detail sectional view.

Fig. 4 is a detail horizontal sectional view, and

Fig. 5 is a detail sectional view on the line 30 5—5 of Fig. 4.

Similar reference numerals designate corresponding parts in all the figures of the drawings.

In the embodiment illustrated, a support 35 in the form of a base 6 is employed, which carries an upstanding guide 7 that is dovetail in cross section. Slidably mounted on the base is a carriage 8 having in its under side a dovetail guideway 9 that receives the 40 guide 7. A suitable adjusting screw 10 is employed for effecting the sliding movement of the carriage in a well known manner.

Slidably mounted upon the carriage 8 and operating transversely of the guide 7 is a 45 work-carrying table 11 having an undercut dovetail guideway 12 that receives a dovetail guide 13 formed upon the said carriage 8. An adjusting screw 14 is employed for moving the work table on the carriage.

50 In each of the guideways and interposed between one of the side walls thereof and the adjacent edge of the guide, is a gib 15 that is set at an inclination as clearly shown and is supported by pins 16 threaded through 55 the adjacent wall of the guideway and entering horizontal openings 17 formed in the

said gib. The adjacent walls of the guideways are furthermore provided with sockets 18 having reduced inner ends 19 forming internal shoulders 20. Plungers 21 are located 60 in the inner ends of these sockets and bear against the outer sides of the gib 15, the plungers having heads 22 that are arranged to abut against the shoulders 20. Springs 23 are located in the outer portions of the 65 sockets, the inner ends of said springs bearing against the heads 22 of the plungers 21 and their outer ends bearing against plug screws 24 threaded into the outer ends of the sockets. The inner ends of the plungers, it will be noted, are inclined to correspond to the inclination of the gib 15. 70

With this construction, it will be evident that the gib are yieldingly pressed against the guides, this tension serving to maintain 75 a snug fit and thus preventing dirt and dust getting between the gib and guides, and thereby affecting the accuracy of the instrument. Furthermore it provides a certain amount of tension that assists in preventing 80 the accidental movements of the adjusting screws.

From the foregoing, it is thought that the construction, operation and many advantages of the herein described invention will 85 be apparent to those skilled in the art without further description, and it will be understood that various changes in the size, shape, proportion and minor details of construction may be resorted to without departing from 90 the spirit or sacrificing any of the advantages of the invention.

Having thus fully described my invention, what I claim as new, and desire to secure by Letters Patent, is:—

1. In metal working apparatus, the combination with a supporting member, of a movable work-carrying member slidable upon the supporting member, one of said members having a dovetail guide, the other 100 having a dovetail guideway that receives the guide, a gib in the guideway interposed between the adjacent edge walls of the guide and guideway, and means carried by one member and pressing against the gib for 105 yieldingly urging the gib against the other member to insure a snug engagement while permitting the necessary sliding movement of the work-carrying member.

2. In metal working apparatus, the combination with a supporting member, of a movable work-carrying member slidable

upon the supporting member, one of said members having a guide, the other having a guideway that receives the guide, pins carried by one member and projecting into the 5 guideway alongside the guide, a gib mounted on the pins, and spring pressed plungers carried by one member and pressing against the gib to hold it in snug engagement with the other member, while permitting the 10 sliding movement of the work-carrying member.

3. In metal working apparatus, the combination with a supporting member having an upstanding dovetail guide, of a work-carrying member having an undercut dovetail guideway in its under face that slidably 15

receives the guide, an inclined gib in the guideway interposed between one of the walls thereof and the adjacent edge of the guide, pins projecting from the work-carrying member into the guideway and engaging the gib, sockets in the work-carrying member, plungers in the sockets having inclined inner ends that bear against the gib, and springs in the sockets behind the 20 25 plungers.

In testimony whereof, I affix my signature in the presence of two witnesses.

CLARENCE C. CRALEY.
